COMBINATION ADAPTOR RING, BOWL AND SPIDER SUPPORT FOR AN ELECTRIC HEAT- ING ELEMENT

Donald M. Cunningham, Pittsburgh, Pa., assignor to
Emerson Electric Co., St. Louis, Mo.

Filed May 19, 1969, Ser. No. 17,224

Term of patent 14 years

Int. Cl. D7—02

U.S. Cl. D81—25

FIG. 1.

FIG. 2.

FIG. 3.

FIG. 5

FIG. 4.

FIG. 1 is a plan view of the upper face of a combination adaptor ring, bowl and spider support for an electric heating element, showing my new design.

FIG. 2 is a section corresponding to the line 2—2 of FIG. 1,

FIG. 3 is a perspective view of the structure,

FIG. 4 is a plan view of the lower face of the structure, and

FIG. 5 is a fragmentary perspective view of a modified form thereof, it being understood that the remainder is the same as the corresponding parts shown in FIGS. 1 through 4.

I claim:

The ornamental design for a combination adaptor ring, bowl and spider support for an electric heating element, substantially as shown and described.
